Des. 232,089

Patented July 16, 1974

232,089

PLAYGROUND SPRINKLER

Anita Margrill, 151 W. 13th St.,
New York, N.Y. 10010

Filed Dec. 6, 1972, Ser. No. 312,677

Term of patent 14 years

Int. Cl. D23—01

U.S. Cl. D23—6

FIG. 1 is a top perspective view of a playground sprinkler embodying my new design;

FIG. 2 is a right side elevational view thereof;

FIG. 3 is a left side elevational view thereof;

FIG. 4 is a front elevational view thereof, the rear being a mirror image of the front shown; and

FIG. 5 is a bottom plan view thereof.

I claim:

The ornamental design for a playground sprinkler, as shown and described.
